UNITED STATES PATENT OFFICE.

WILLIAM C. HOFFMEISTER, OF MOSSY CREEK, TENNESSEE.

DOUBLE TRY-SQUARE.

SPECIFICATION forming part of Letters Patent No. 235,434, dated December 14, 1880.

Application filed October 15, 1880. (No model.)

To all whom it may concern:

Be it known that I, WILLIAM C. HOFFMEISTER, of Mossy Creek, in the county of Jefferson and State of Tennessee, have invented a new and Improved Double Try-Square, of which the following is a specification.

The object of this invention is to provide an improved device for the convenience of laying out, marking, or scribing work.

10 The invention consists of two ordinary try-squares joined together side by side, a suitable and adjustable distance apart, by a metal plate and screws or other suitable device, so that said square may be adjusted to straddle boards of different thicknesses.

Figure 1 represents a side elevation of the improved combination-square; Fig. 2, an end elevation of the same. Fig. 3 indicates its use for cutting in siding-boards on a house. Fig. 20 4 indicates its application for scribing irregular faces. Fig. 5 shows the manner of setting the cuts in putting down wash bases or boards in houses. Fig. 6 shows its use in marking the projecting ends of boards that are to be cut off, as in boxing, &c. Fig. 7 shows its application for ascertaining the projections of table-leaves, roofs, &c. Fig. 8 shows its application to the same purpose as shown in Fig. 3, excepting that the end of the board is to be mitered. Fig. 9 shows the application of the square in marking a head-joint.

Similar letters of reference indicate corresponding parts.

The ordinary try-square consists of a thin blade of metal projecting at right angles from a thick block of wood or metal forming a species of handle, the edges of both blade and block being accurately straight.

In the drawings, A' A' represent two ordinary try-squares set side by side parallel with each other and held together by a metal plate, B, secured to their backs by screws or other convenient devices, a a, thereby forming my improved double square A. The screw-holes b of the said plate B are slotted, as shown, to permit the adjustment of the squares A' A' nearer to or farther from each other, for convenient application to boards of different thicknesses.

Some of the advantages of this double square A over those in common use are indicated in the drawings.

In Figs. 3, 6, and 8 the square A is shown set straddling on boards c, with an inner arm set against a guiding object, such as a window-casing, side of a box, or rafter, d, so that the said boards c can be marked or scribed on the face or outside, thus enabling the operator to saw the boards accurately even if the edge of casing is not square, or is not put on square, as sometimes happens, and saving time and labor in try-fitting, &c.

In Fig. 4 the square A is shown applied to an irregular object, f, such as a strip of molding or cornice, the short wooden arm of the said square A being set against the straight edge of the said molding f, and the long metal arm extended over the irregular face thereof. The two long arms of the square A, being parallel and apart from each other, afford a correct 70 guide and support for the scratch-awl C in scribing a straight line upon the irregular face of said object f.

In Fig. 7 the position of the square A indicates the manner of ascertaining the width of 75 the projection of a table top or leaf, g, wherein the square A is made to straddle the edge of said table top or leaf g, so that an end of the square arm shall abut against the table-frame beneath said top or leaf g, while the other long 80 arm shall rest on the top of said leaf or top, so that with the scratch-awl C the proper measurement may be marked off.

In Fig. 5 the square A is made to straddle the base-board h, whereby said square can 85 take as a guide the inner edge of the upright molding i.

In Fig. 9 the square A is shown applied to boards k for the purpose of marking a head-joint, said square A being made to straddle 90 the boards k, with its short arm parallel with the straight edge of said boards k, so that the ends of one or both of said boards k can be scribed at right angles to the edges.

This tool can also be used for all purposes 95 to which the ordinary try-square is adapted, and is easily adjusted, simple, and accurate, and the cost of construction is but trifling, and

by removing the connecting-plate B two try-squares of ordinary construction are furnished.

I do not limit or confine myself to the exact form of the device or method herein shown for joining or adjusting the two try-squares, as other devices or methods that will produce the results herein mentioned may be used.

Having thus fully described my invention, I claim as new and desire to secure by Letters Patent—

1. As an improved article of manufacture, a double try-square made substantially as herein shown and described, consisting of two try-squares held together side by side by fast-

enings that permit of the adjustment of the 15 squares to or from each other, as set forth.

2. The combination, with the try-squares A' A', of the slotted metal plate B, substantially as herein shown and described, whereby the said squares may be adjusted to or from each other, as and for the purpose set forth.

3. In a double try-square, the slotted plate B, constructed substantially as and for the purpose described.

WILLIAM CARMICHAEL HOFFMEISTER.
